(57) CLAIM

The ornamental design for a shoe insole, as shown and described.

DESCRIPTION

FIG. 1 is a top right perspective view of a shoe insole for a right foot;

FIG. 2 is a top left perspective view thereof for a left foot, being a mirror image of that for the right foot;

FIG. 3 is a front view thereof;

FIG. 4 is a rear view thereof;

FIG. 5 is a right side view thereof;

FIG. 6 is a left side view thereof;

FIG. 7 is a bottom view thereof for a right foot;

FIG. 8 is a bottom view thereof for a left foot, with section lines;

FIG. 9 is a first sectional view take along line 9-9 of FIG. 8;

FIG. 10 is a first sectional view take along line 10-10 of FIG. 8; and,

FIG. 11 is a first sectional view take along line 11-11 of FIG. 8.

1 Claim, 7 Drawing Sheets
